UNITED STATES PATENT OFFICE.

CHARLES HENRY SHAW, OF DENVER, COLORADO.

ROCK-DRILL.

No. 830,744.

Specification of Letters Patent.

Patented Sept. 11, 1906.

Application filed September 21, 1905, Serial No. 279,491.

To all whom it may concern:

Be it known that I, CHARLES HENRY SHAW, a citizen of the United States, residing at Denver, in the county of Denver and State of Colorado, have invented certain new and useful improvements in Rock-Drills; and I do hereby declare the following to be a full, clear, and exact description of the invention, such as will enable others skilled in the art to which it appertains to make and use the same.

This invention relates to improvements in rock-drills, and particularly to drills in which means is provided for directing cleaning agents into the hole drilled for clearing it of cuttings or other debris.

It is the object of the invention, among other things, to provide a drill in which air or water, or both, alternately may be delivered through the drill into the hole cut for clearing the same; and it is a further object of the invention that the drill shall be so constructed that one of the clearing agents may be used for feeding or holding the drill to its work.

With these and other objects in view the invention comprises certain novel constructions, combinations, and arrangements of parts, as will be fully described and claimed.

In the accompanying drawings, Figure 1 is a central longitudinal sectional view through the principal part of a rock-drill, the passages for delivering air or water to the hollow drill being particularly set forth, taken on line 1 1 of Fig. 2. Fig. 2 is an end elevation of the drill-casing, the hollow piston carrying the same being shown in transverse section, as on line 2 2 of Fig. 6. Fig. 3 is a central longitudinal section through the principal portion of the drill and its casing, the section being taken along the line of the water-inlet passage, 40 as on line 3 3 of Fig. 2. Fig. 4 is a detail sectional view of a portion of the casing, showing the three-way pressure-controlling valve. Fig. 5 is a transverse sectional view through the drill-casing upon the line *a b* of Fig. 3. Fig. 6 is a view in elevation, partially broken away, of the drill-casing and with the drill-supporting means shown in longitudinal section.

The present invention embraces a rock-drill mechanism in which air or water under pressure is led through a hollow drill into the hole which is cut thereby, so as to clear the same from cuttings, dirt, or other debris, and the structure is such that air may be used alone or water alone, or the two fluids may

be used interchangeably. The drill is also so constructed that fluid under pressure may be used for holding the drill to its work, the fluid being led into an expandible feeding device.

I have illustrated in the drawings the preferable manner of constructing my improved drill, and in the said drawings 1 indicates the drill-casing, which is formed with a central compartment and guides for a reciprocating hammer or piston 2. The structure of the piston or hammer 2 may be a usual or ordinary one, and fluid under pressure for operating the same is introduced through a passage 5, formed in the casing and leading from an inlet 4 past a controlling-valve 6. I preferably operate the said hammer by pneumatic power, the connection at 4 being with compressed-air-supply pipe. Since the particular operation of the piston or hammer 2 does not form an essential feature of the present invention, it does not require a full description at this point.

One end of the drill-casing receives the drill 3, which will be hereinafter more fully described. The other end of the casing is secured to the drill supporting and feeding mechanism, which is operable by the air-pressure which is delivered into the casing of the drill. One end of the said casing 1 is bored to a suitable size to receive the enlarged end of a supporting and feeding piston 9. This bored portion of the casing is provided with internal threads which engage external threads formed upon the end of said piston 9. In the said threaded bore of the casing an annular depression or groove 10 is formed for distributing the fluid introduced into the casing through the inlet 4. The external screw-threads upon the inner end of the piston 9 are interrupted opposite the groove 10 to complete the formation of the distributing-passage. Fluid under pressure is led from the passage 5 to the said distributing-groove 10 by a passage 7, formed in the casing 1 and clearly illustrated in Figs. 1 and 6.

The piston 9 is made hollow for the greater portion of its length, the said piston being provided with a central bore or passage 16. The inner end of the said piston 9 is closed, and communication is established between the annular distributing-groove 10 and the bore 16 of the piston 9 through passages 8, which extend across the end of the said bore 16 and to the periphery of the threaded

portion of said piston. I usually employ about four passages 8, which are arranged radially in the piston 9 and generally project from the center thereof at angles of about 5 ninety degrees from each other. It will thus follow that fluid introduced into the distributing-groove 10 at any point will find its way through the passages 8 into the bore of the piston 9 and may then be led into the expansible 10 holder for forcing the drill to its work.

The piston 9, which carries and supports the casing 1, is preferably rigidly held in position in the threaded bore by means of a lock-nut or collar 11, which is screwed upon the 15 threads of the piston 9 and is provided with a peripheral flange having ratchet-teeth 12 upon its inner face. The said ratchet-teeth 12 are engaged by a reciprocating latch 13, mounted in a socket formed in the casing 1, 20 the said latch being normally forced against the ratchet-teeth by a coiled spring 14, mounted in the said socket. An operating projection 15 is formed upon the latch and projects through a slot in the casing by which 25 the latch may be retracted when the piston with its locking-nut or collar 11 is to be unscrewed from its position.

As already intimated, the piston 9 forms one member of the expansible support for the 30 drill, the other member being made up of a sleeve or cylindrical casing 42, which telescopes upon the other end of the said piston 9. The end of the sleeve 42 which is slipped upon the piston carries a cap 45, which holds 35 a packing 46 in place. The outer end of the sleeve 42 carries a plug 43, into which is screwed a pin 44. A sufficient space is left between the end of the piston 9 and the plug 43 to form a fluid-receiving chamber, which 40 is in communication with the bore 16 of the said piston. The end of the piston 9 which extends into the sleeve 42 is also packed, the packing, as at 51, being seated on an annular shoulder formed upon the said piston, while 45 a nut 50 holds the same in place. The nut 50 is carried upon the threads of a set-screw 47, which is screwed into the end of the said piston 9. A lock-nut 52 holds the said nut 50 in place. The set-screw 47 is provided 50 with a central bore 49 for connecting the bore 16 with the pressure-chamber 48. It will be seen that when placing the pin against a support, wall, rock, or other abutment opposite the point to be drilled and introducing fluid 55 under pressure through the bore 16 into the chamber 48 the piston 9 will be forced outwardly in the casing 42 for forcing the drill-casing and the drill against the material being operated upon. As stated heretofore, 60 air under pressure is preferably used for this purpose. A handle 17 is secured in the side of the casing 1, as shown in Figs. 1, 2, and 6, by which the drill may be properly directed and steadied in position.

65 Suitable provision is also made for deliver-

ing water to the hollow drill 3, and a water connection is established at 18 with any suitable source of water delivered under pressure. Leading from the water-inlet passage 18 and extending longitudinally through the 70 walls of the casing 1 is a passage 23, the said passage extending to a point opposite a hollow portion of the drill 3. At this point the passage 23 communicates with oppositely-diverging passages 24, which lead into chambers 25, formed in oppositely-extending enlargements provided at the drill end of the casing 1. Near the inlet end of the passage 23 a three-way valve 19 is mounted in the casing, the said valve having a bore or transversely-extending port 20, preferably of the same size as the passage 23. Extending at right angles to the said transverse port 20 is a smaller port 21. When the valve 19 is set, 80 as shown in Fig. 3, communication is established between the water-supply and the passage 23 and water is led into the chambers 25 and thence into the hollow drill, as will be hereinafter described. When the air under pressure is to be led to the drill, the passage 90 23 is also used, and in order to deliver the air thereto a connecting-passage 22 is formed in the casing so as to lead from the distributing ring or groove 10 to the valve-seat of the valve 19, as shown in Figs. 3 and 4. When 95 the valve 19 is in the position shown in Fig. 3, the solid portion of the valve is brought across the end of the passage 22, and the air is checked at that point. When, however, air is to be used at the drill in the place of 100 water, the valve 19 is turned to the position shown in Fig. 4. This operates to cut off the water-supply at the inlet 18 and communication is established through the ports 20 and 21 of the valve between the passage 22 and 105 the passage 23. In this manner the air under pressure which is normally maintained in the distributing-groove 10 will be led to the drill. The valve 19, as well as the valve 6, 110 may be controlled in any suitable manner 115 and usually by a simple hand-lever or other form of handle—such, for instance, as shown in Fig. 6.

The manner of mounting the drill in the casing and the mode of delivering the fluids 120 under pressure thereto forms an important feature of the invention and will now be set forth. The inner end of the drill 3 is formed with a many-sided end, being preferably hexagonal in shape, the hexagonal portion 125 projecting through a bushing 30, which is mounted in a recess in the casing 1, said bushing having at its inner end a portion which fits snugly upon the hexagonal part of the drill. The inner end of the drill projects 130 beyond said bushing and into the hammer or piston chamber a sufficient distance to permit of its receiving the strokes of said hammer or piston. The bushing 30 operates to prevent the turning of the drill in the 135

casing 1. Of course the drill may be turned in the hole which is bored by turning the casing 1 through the agency of the handle 17.

At a point adjacent to the bushing 30 the drill 3 is somewhat enlarged and is formed with oppositely-arranged flat faces. A transverse bore or passage 27 extends through said enlarged portion 26 and communicates with the bore or central passage 28 of the said drill 3. In delivering the fluid under pressure to the hollow drill it is desirable that connecting means be employed which is capable of forming a tight joint with the drill, but which will not interfere in the least with the withdrawal or replacement of the drill.

As shown in Fig. 1, the oppositely-extending enlargements at the drill end of the casing are formed with sockets or chambers 25, in which are seated bushings 31, and in the said bushings are movably-arranged pistons 32. The inner ends of the pistons are extended through the bushings 31 and to a point adjacent to the drill and are formed with sockets which receive and hold yielding coupling-tubes 33. The ends of the said coupling-tubes 33 are adapted to fit over the outer ends of the passage 27 in the drill, and when the said tubes are pressed against the drill a tight joint will be formed at this point for the delivery of fluid into the passages of the drill. A packing-washer 38 is secured upon the head of each piston 32, so as to form a snug joint between the same and the inner surface of the bushings 31. These washers, as well as the tubes 33, are preferably formed of rubber. The washers 38 are clamped in position by metallic washers 39 and set-screws 34. The said set-screws 34 are formed with central bores 35 for establishing communication between the chambers 35 and the tubes 33. Springs 37, preferably of the coiled type, are seated within the bushings 31 and operate to carry the pistons away from the drill when there is no pressure in the chambers 25. The tubes 33 will thus be retracted from their engagement with the drill when the pressure is released. It will be evident from this construction that as soon as either air or water under pressure enters the chambers 25 the pistons 32 will be instantly driven inwardly to firmly press the tubes 33 against the squared faces of the drill around the passage 27. As soon as the pressure is relieved by turning it off at any suitable point the springs 37 will carry the pistons 32 outwardly again and separate the tubes 33 from the drill 3, and the drill can be removed or replaced as required.

In the operation of the drill the pin 44 is set against a suitable abutment and fluid under pressure is turned on through the inlet 4. It will immediately pass through the passage 7 into the distributing-groove 10 and thence through the piston 9 into the chamber 48 to force said piston outwardly and the drill

against its work. By turning the valve 6 the same air-pressure is delivered to the hammer 2 for operating the drill. In the meantime if water is to be used in clearing the drill-hole the valve 19 is turned as indicated in Fig. 3, and water under pressure introduced at 18 is permitted to pass through the passage 23 and thence through the passages 24 into the chambers 25. The pressure of the water will immediately set the tubes 33 against the drill, and the water may then pass into the hollow bore of the drill to be delivered into the drill-hole. If it is desired to use air instead of water for the drill, the valve 19 is turned, as in Fig. 4, so as to cut off the water-supply and establish connection between the passage 23 and the distributing-groove 10. Air will then pass through the valve 19 and reach the drill 3 in the same manner as described with respect to the water. It will thus be seen that air or water under pressure may be used in the drill for clearing the cuttings and that the change from one to the other can be quickly accomplished merely by the turning of the valve 19. It is sometimes advantageous to use air and water under pressure in alternation, and of course the mechanism described is eminently practical for this purpose. The mechanism is simple and not likely to get out of order and yet very effective for the purposes desired.

The outer ends of the chambers 25 are closed by removable plugs 40, which are screwed into place, as shown in Fig. 1. By this means ready access is had to the coupling mechanism mounted in these chambers.

It will be noted that the flexible tubes 33 permit of the rapid reciprocating strokes of the drill under the action of the hammer and yet maintain a close joint between the parts.

Having thus described my invention, what I claim as new, and desire to secure by Letters Patent, is--

1. In a drill mechanism, a casing, a hollow drill-shank inserted in the casing and provided with a lateral opening, a cylinder formed within the casing adjacent the shank, a hollow piston mounted to reciprocate within the cylinder, an elastic packing carried by the piston and in contact with the shank, a duct forming communication between the casing and the cylinder and opening in the rear of the piston, and means to admit fluid under pressure to the casing.

2. In a drill mechanism, a casing, a hollow drill-shank inserted in the casing and provided with a lateral opening, a cylinder formed within the casing adjacent the shank, a hollow piston mounted to reciprocate within the cylinder; a hollow elastic packing carried by the piston, and forming communication between the lateral opening of the shank and the passage through the piston, a duct forming communication between the casing

and the cylinder and opening in the rear of the piston, and means to admit fluid under pressure to the casing.

3. A drill mechanism comprising a hollow drill, a fluid - operated hammer therefor, means for delivering fluid under pressure to points adjacent to the hollow drill, and reciprocating hollow couplings arranged to be clamped against the drill under the action of the pressure which passes therefrom to the drill.

4. A drill mechanism comprising a hollow drill, means for driving the drill, means for delivering fluid under pressure to a point adjacent to the drill, hollow pistons for establishing communication with the drill, yielding couplings carried by said piston, and means for retracting the piston when not under pressure, the fluid under pressure operating to hold the yielding couplings tightly against the drill.

5. A drill mechanism comprising a casing, a hollow drill, and a drill-driving mechanism, the casing being provided with passages for delivering fluid under pressure to the hollow drill, normally released couplings capable of establishing communication with the drill for said fluid, springs for retracting said couplings, and means whereby the fluid forces the couplings against and into communication with the drill, and means for holding the drill from turning with respect to said couplings.

6. A drill mechanism comprising a casing, a hollow drill, and a drill-driving device, the casing having passages for delivering fluid under pressure to the hollow drill, oppositely-arranged couplings for establishing connection with the drill comprising reciprocating pistons, yielding tubular extensions therefor, guiding bushings for the pistons, springs for normally forcing the pistons away from the drill, and means for packing the movement of the pistons, the fluid under pressure operating to drive the pistons in contact with the drill with sufficient force to prevent the leakage of fluid at this point, the springs operating to release the drill when the pressure is checked.

5c 7. A drill mechanism comprising a casing, capable of receiving a hollow drill, a drill-driving device therefor, the casing being provided with a longitudinally-extending passage, branching passages being also provided and leading to points on opposite sides of the drill, piston-couplings mounted in the casing upon opposite sides of the drill for establishing a connection with the hollow portion of the drill, and retracting means for said piston-couplings, the fluid under pressure which

is to be delivered to the drill operating to force the couplings toward each other to grip the drill between them.

8. In a drill mechanism, a casing, a hollow drill-shank inserted in the casing and provided with a lateral opening, a cylinder formed within the casing adjacent the shank, a hollow piston mounted to reciprocate within the cylinder, a hollow elastic packing carried by the piston to form communication between the lateral opening and the passage through the piston, a resilient member bearing against the piston and arranged to hold the elastic packing normally out of contact with the shank, and means to admit fluid under pressure in the rear of the piston to force the elastic packing into contact with the shank, and to complete the passage from the cylinder through the piston and packing into the hollow shank.

9. A drill mechanism comprising a casing, a hollow drill mounted in said casing, means within the casing for driving the drill, a cylinder, a piston within the cylinder and carrying the casing and having an annular fluid-distributing groove formed around it in communication with a source of compressed-air supply, means for introducing liquid under pressure into the casing, the casing being provided with a passage leading therefrom to the hollow drill, a valve provided with a transverse port, and a lateral port, and so arranged that the turning of the valve selectively cuts off either the air or the water from the passage which leads to the drill.

10. In a drill mechanism, a casing, a hollow drill-shank inserted in the casing and provided with a lateral opening, a cylinder formed within the casing adjacent the shank, a hollow piston mounted to reciprocate within the cylinder, a hollow elastic packing carried by the piston and arranged to form communication between the lateral opening and the passage through the piston, a resilient member arranged to bear against the piston and hold the packing normally out of contact with the shank, a duct forming communication between the casing and the cylinder and opening in the rear of the piston, and means to admit fluid under pressure to the casing, and through the medium of the duct against the rear of the piston to hold the elastic packing in contact with the hollow shank.

In testimony whereof I affix my signature in presence of two witnesses.

CHARLES HENRY SHAW.
